UNITED STATES PATENT OFFICE

140,088

DESIGN FOR A CHILD'S TOY OR THE LIKE

Charles E. Russell, Chicago, Ill., assignor to Amatoy Corporation, Chicago, Ill., a corporation of Illinois

Application October 5, 1944, Serial No. 115,630

Term of patent 14 years

(Cl. D34—15)

To all whom it may concern:

Be it known that I, Charles E. Russell, a citizen of the United States, residing at Chicago, in the county of Cook and State of Illinois, have invented a new, original, and ornamental Design for a Child's Toy or the like, of which the following is a specification, reference being had to the accompanying drawings, forming a part thereof.

In the drawings—

Fig. 1 is a side perspective view of a child's toy showing my new design,

Fig. 2 is a plan view thereof, and

Fig. 3 is an end elevational view thereof.

I claim:

The ornamental design for a child's toy or the like, as shown.

CHARLES E. RUSSELL,
